(57) **CLAIM**

The ornamental design for a vented end cap for medical tube, as shown and described.

DESCRIPTION

FIG. 1 is a bottom perspective view of one embodiment of a vented end cap for medical tube showing my new design; FIG. 2 is a top perspective view of the design of FIG. 1; FIG. 3 is a side view of the design of FIG. 1, with all sides being identical; FIG. 4 is a bottom view of the design of FIG. 1; FIG. 5 is a top view of the design of FIG. 1; FIG. 6 is a cross-sectional side view of the design of FIG. 1; FIG. 7 is a cross-sectional side view of the design of FIG. 1 rotated 90 degrees from the view of FIG. 6; FIG. 8 is a perspective view of another embodiment of a vented end cap for medical tube showing my new design; FIG. 9 is a top perspective view of the design of FIG. 8; FIG. 10 is a side view of the design of FIG. 8, with all sides being identical; FIG. 11 is a bottom view of the design of FIG. 8; FIG. 12 is a top view of the design of FIG. 8; FIG. 13 is a cross-sectional side view of the design of FIG. 8; FIG. 14 is a cross-sectional side view of the design of FIG. 8 rotated 90 degrees from the view of FIG. 13; FIG. 15 is a perspective view of another embodiment of a vented end cap for medical tube showing my new design; FIG. 16 is a top perspective view of the design of FIG. 15; FIG. 17 is a side view of the design of FIG. 15, with all sides being identical; FIG. 18 is a bottom view of the design of FIG. 15; FIG. 19 is a top view of the design of FIG. 15; FIG. 20 is a cross-sectional side view of the design of FIG. 15; and, FIG. 21 is a cross-sectional side view of the design of FIG. 15 rotated 90 degrees from the view of FIG. 20.
